UNITED STATES PATENT OFFICE.

ALBERT MATTHEWS AND ALFRED MILLER, OF WINNIPEG, MANITOBA, CANADA.

WATER-HEATING APPLIANCE FOR AUTOMOBILES.

1,121,741.

Specification of Letters Patent. Patented Dec. 22, 1914.

Application filed July 25, 1913. Serial No. 781,229.

To all whom it may concern:

Be it known that we, ALBERT MATTHEWS and ALFRED MILLER, both of the city of Winnipeg, in the Province of Manitoba, Canada, have invented certain new and useful Improvements in Water-Heating Appliances for Automobiles, of which the following is the specification.

The invention relates to a heating appliance attachable especially to automobiles and the object of the invention is to provide a device whereby the water customarily contained within the water jackets, radiator and connecting pipes of an automobile engine can be kept heated when the engine is idle thereby avoiding the possibility of the water freezing in these parts in countries where low temperatures are experienced.

With the above objects in view the invention consists essentially in a heater located in any suitable position on the automobile, the heater being supplied with a boiler, inlet and outlet pipes connecting the heater with the water cooling system of the engine, the parts being arranged and constructed as hereinafter more particularly described and later pointed out in the appended claims.

Figure 1 represents a side view of the front end of an automobile chassis showing our invention applied. Fig. 2 represents a plan view of the same. Fig. 3 represents an enlarged detailed vertical sectional view through the boiler. Fig. 4 represents an enlarged detailed horizontal sectional view through the boiler. Fig. 5 represents an enlarged detailed back view of the boiler casing removed.

In the drawings like characters of reference indicate corresponding parts in each figure.

1 represents the frame of an automobile carrying as usual a radiator 2, a dash-board 3, foot boards 4 and engine 5, the engine presenting in the present instance the cylinders 6, 7, 8 and 9.

10 represents a water lead pipe connected with the top of the radiator and communicating through branch pipes 11, 12, 13 and 14 with the customary water jackets of the several cylinders.

15 represents a return water pipe connected with the lower portion of the radiator and communicating with the various

cylinder jackets through the branch pipes 16, 17, 18 and 19.

The above parts are all of ordinary construction and form no part of our invention.

In actual practice there is a circulation of water through the cylinder jackets and radiator and the lead and return pipes, this water being utilized to keep the cylinders from heating unduly when in use, the water circulating being cooled in passage through the radiator.

In countries where cold weather is experienced considerable trouble is caused by the water actually freezing in the jackets 70 lead and return pipes or the radiator when the engine has been left standing idle, this occurring particularly where one is making long stops and does not desire to leave the engine running. To overcome this difficulty 75 we have provided the following attachment which is in reality a heater suitably connected so that a circulation of hot water can be established through the jackets, lead and return pipes and the radiator, that is 80 through the water cooling system of the engine when the engine is out of commission.

The heater 20 in the present instance is connected to the dash-board 3 in any suitable manner and it comprises a tubular water containing boiler 21 and a source of heat the source of heat being indicated in the present instance by a gas burner 22^m the gas burner being positioned directly beneath the boiler. The burner is carried at the upper end of a gas pipe 23 which passes downwardly to the foot boards 4 where it is connected with a gas tank 24. We do not consider it necessary to supply a special 85 gas tank as a great many of the automobiles now on the market are fitted with gas tanks, these being part of the lighting system.

25 represents a valve located within the length of pipe 23 controlling the flow of 100 gas through the burner.

26 is an outlet pipe passing from the top of the boiler to the radiator, this pipe entering the radiator at a point below the entrance of the pipe 10 to the radiator. It 105 is to be noticed that this pipe is actually in a lower horizontal plane than the pipe 10.

27 is a branch pipe connecting the pipes 26 and 10 more or less centrally of their length.

28 is an inlet pipe opening to the bottom of the boiler and communicating with the bottom of the radiator. The boiler is inclosed within an asbestos lined casing 29 which has the lower end thereof extending downwardly to protect the burner. The casing is in the form of a vertically split cylinder having the two sections hinged at one side as indicated at 30 and designed 10 to close around the boiler. The edges of the cylinder sections at the other side are notched out as indicated at 31 to admit the pipes 26 and 28 when the same is closed around the boiler. A releasable lock 32 15 such as a hook and eye is applied on the latter edges of the casing so that they can be fastened together.

33 is an asbestos lined funnel shaped top fitting the casing and closing over the top 20 of the boiler. The latter parts are constructed so that the casing can be readily removed to inspect the boiler. This is done by lifting off the top and undoing the releasable lock.

25 With the above apparatus installed on an automobile it is only necessary for one to turn the valve 25 and then light the gas escaping through the burner, the resultant flame heating the water in the boiler and 30 so causing a circulation of heated water through the cylinder jackets, pipes and radiator and thereby preventing the possibility of burst pipes jackets or radiator through freezing as commonly occurs.

35 In actual practice we find that the water flows from the boiler through the pipe 26 till it reaches the pipe 27 where it passes upwardly and branches into the pipe 10 flowing in opposite directions in said pipe at 40 the point of entrance. From the pipe 10 it is distributed to the various cylinder jackets and also the radiator the flow to the jackets being through the branch pipes 11, 12, 13 and 14. The water passing into the 45 jackets is released through the pipes 16, 17, 18 and 19 and collected by the pipe 15 which passes it directly to the bottom of the radiator the pipe 28 then returning the 50 water to the bottom of the boiler thus completing the circulation. We find that in actual practice there is no flow through that portion of the pipe 26 appearing between the branch pipe and the radiator when the appliance is in use. This is explained by 55 the fact that the pipe 26 enters the radiator below the water level in said radiator while the pipe 10 enters it above the water level.

The pipe connections above described provide a very even distribution and flow of 60 water through the jackets and radiator, the circulation being established through all of

these parts very quickly after the burner has been lighted. We do not however wish to be restricted to the precise form of heater used as various other forms could be readily suggested and applied to equal advantage nor to the particular way in which the inlet and outlet pipes are connected up with the engine water cooling system. These details can be arranged to comply best with 70 the various styles of automobiles now found on the market.

What we claim as our invention is:—

1. In an automobile the combination with the engine, the water jackets, the radiator 75 and the lead and return pipes connecting the radiator with the water jackets, said parts comprising the water cooling system of the engine, of a boiler mounted in any suitable location on the automobile, means 80 for applying heat to the boiler, an outlet pipe passing from the top of the boiler to the top of the radiator, a branch pipe connecting the outlet pipe with the lead pipe aforesaid and an inlet pipe connecting the 85 bottom of the radiator with the bottom of the boiler, as and for the purpose specified.

2. In an automobile, the combination of a car having an engine, a water-jacket for the engine, a radiator located in the front 90 of the car, a heater, an outlet pipe connecting the upper part of the heater with the upper part of the radiator, a lead pipe communicating with the radiator above the outlet pipe, a branch pipe connecting the lead 95 and outlet pipes, means connecting the lead pipe with the top of the water jacket, a return pipe connecting the lower end of the heater with the lower end of the radiator and a return pipe connecting the lower end 100 of the water jacket with the lower end of the radiator.

3. In an automobile, the combination of a car having an engine, a radiator at the front 105 of the car, a water jacket for the engine, outlet and lead pipes connecting the upper portion of the radiator with the heater and the water jacket respectively, and return pipes connecting the radiator with the heater and the water jacket respectively, the 110 point of connection between the radiator and the outlet pipe being below the point of connection between the radiator and the lead pipe and a branch pipe connecting the lead 115 and outlet pipes.

Signed at Winnipeg this 28 day of May 1913.

ALBERT MATTHEWS.
ALFRED MILLER.
